UNITED STATES PATENT OFFICE.

LADISLAV O. KOZAR, OF WILKES-BARRE, PENNSYLVANIA, ASSIGNOR OF ONE-HALF TO
JOSEPH MURGAS, OF WILKES-BARRE, PENNSYLVANIA.

ELECTRIC-ARC LAMP.

No. 928,127.

Specification of Letters Patent.

Patented May 25, 1909.

Application filed March 17, 1909. Serial No. 484,032.

To all whom it may concern:

Be it known that I, LADISLAV O. KOZAR, a subject of the Emperor of Austria-Hungary, and resident of Wilkes-Barre, in the county 5 of Luzerne and State of Pennsylvania, have invented certain new and useful Improvements in Electric-Arc Lamps, of which the following is a specification.

This invention relates to means for regulating electrodes and is particularly adapted for use in connection with electric arc lamps. It may, in fact, be employed to great advantage wherever a gap of constant length is necessary or desirable.

15 The object of the invention is to provide improved means of the character described as will be hereinafter set forth.

In the accompanying drawings which illustrate the invention,—Figure 1 is a side 20 elevation of an arc lamp embodying the invention; Fig. 2 is a side elevation, partly broken away and certain parts removed, on a plane ninety degrees removed from that upon which Fig. 1 is taken; Fig. 3 is a side elevation 25 of an electrode frame; Fig. 4 is an enlarged view of the releasing magnet and contacts; Fig. 5 is an enlarged perspective view of a detail showing the manner of engagement of an electrode with the equalizing rod; Fig. 6 is a diagram of connections; and Fig. 30 7 is an enlarged sectional view of the magnet and attached parts for swinging the electrodes.

Referring to the drawings, the apparatus 35 comprises a supporting frame upon which are mounted the two swinging electrode frames A and B, which, with the electrodes they carry, tend to separate under the action of gravity, an electro-magnet C and mechanism 40 for bringing the electrodes into contact for striking the arc, arc deflecting magnets D and E, a releasing magnet F for deenergizing the electro-magnet C and thereby releasing the electrodes from the means which 45 draws them together, a spring secured dashpot G for retarding the movement of the electrodes and an adjustable resistance H for regulating the strength of the arc deflecting field.

50 The supporting frame comprises a plate 1 to which are secured the cross bars 2 and 3, the bars being insulated from the plate. The supporting frame also comprises rods 4 and 5 depending from the plate 1 and carry-

ing at their lower ends the arc deflecting 55 magnets and their cores.

The electrode frames are pivoted to the bars 2 and 3, and as these frames are alike, a description of one of them is sufficient. The frame B comprises the plate 7 pivoted at its 60 ends and the plate 8 to which are fixed the inclined pair of tubes 9 and 10 which serve as guides for the sticks of carbon or other suitable material which constitute the electrodes. The sticks are free to move downwardly under the action of gravity and abut at their lower ends whereby they are mutually supported. In order that the sticks may move downwardly evenly and steadily, a rod 11, preferably bowed as shown, is located at one side of the tubes 9 and 10. This rod 11 engages with the electrodes in such manner that they may move longitudinally but not transversely thereof, and is guided in its movements by means of a guide 70 rod 12, fixed to the plates 7 and 8, on which slides a sleeve 13 to which the rod 11 is secured. The engagement of the rod 11 with the carbons may be effected by means of the carbon holders 14 and 15 secured to the carbons and provided with lugs 16 and 17 extending through slots in the tubes 9 and 10 and having holes through which the rod 11 extends. The arrangement of the rod at one side of the carbon guides is an extremely 75 simple one and very efficient. As the carbons burn away, they move downwardly and their abutting ends which constitute one pole of the arc always maintain a fixed position with relation to the apparatus. This being 80 true of both pairs of carbons, the arc gap is maintained constant.

To limit the separation of the electrodes under the action of gravity, the electrode frames are respectively connected by the 95 links 18, 19, 20 and 21, with the rod 22, which is vertically movable, and its ends are secured to the sleeves 23 and 24 which slide upon the rods 4 and 5. The adjustably secured stops 32 and 33 serve to limit the 100 downward movement of the rod 22 and therefore the separation of the electrodes. The links 18, 19, 20 and 21 are insulated from the rod 22 and are free to swing thereon, the links 18 and 19 being pivoted to the 105 electrode frame A and the links 20 and 21 being pivoted to the frame B.

The pairs of electrodes may be moved into

contact by hand to strike the arc, but to do this automatically, the electro-magnet C is provided. This magnet is adjustably supported upon the rods 4 and 5 and its plunger 123 is secured to the rod 22 so that when the magnet is energized and the plunger lifted, the electrodes will be brought into contact.

To release the electrodes so that they may separate after having been brought together, the contacts 124 and 125 and contact maker 26 are insulated from each other and are inserted in the circuit of the magnet C. The contact maker is mounted on the armature of the magnet F, and connects the contacts together when the magnet F is de-energized. When the magnet F is energized the contact maker is raised and the circuit of the magnet C is broken and the electrodes separate until arrested by the stops. An insulating cover 34 for the contact may be provided.

In order that the separation of the electrodes may be retarded and the arc gradually drawn, the dash-pot G is provided. The dash-pot is supported by the plate 1 and its piston is connected with the rod 22. It has been found, especially where alternating currents of low frequency are employed, that the electrodes are not held in firm contact by the magnet C but that a trembling contact exists. To remedy this and insure a firm contact and certain striking of the arc, the dash-pot is suspended by a spring 27 and the cylinder of the dash-pot is provided with a projection 28 which is operated as a plunger by the magnet C. When the magnet is energized, the dash-pot is drawn downwardly and the spring is placed under tension. When the magnet is de-energized, the dash-pot is drawn upwardly by the spring and the electrodes are pressed firmly together. Then, after the piston has descended to a point where the tension of the spring is relieved, the electrodes will slowly separate.

The resistance H may be of any suitable material and construction and supported at any convenient place.

The poles 29 and 30 of the arc deflecting magnets are located at the sides of the arc gap, so that the flux passing between them will pass through the upper part of the gap and transverse to the arc. They may, however, be arranged in any other desired relation to the arc to produce desired results, as will be well understood by persons skilled in the art.

An examination of the diagram shown in Fig. 6 will show that the resistance H and the magnet D are connected in parallel with each other and in series with the magnet F and the gap while the magnet C is connected across the terminals 31 and 32 of the lamp, the contacts 24 and 25 being inserted in its

circuit. The part lettered D in this figure is intended to represent diagrammatically the magnet E as well as the magnet D.

The operation of the lamp may now be described as follows: When no current is passing through the apparatus, the pairs of electrodes will be separated as far as is permitted by the stops and the circuit of the magnet C will be closed. If now, current be supplied the magnet C will be energized, the electrodes drawn into contact and the dash-pot drawn downwardly placing the spring under tension. Current will then pass through the electrodes, the magnet F, the magnets D and E and the resistance H. The circuit of the magnet C will be broken and the electrodes and the dash-pot will be released. The spring will hold the electrodes firmly in contact until the dash-pot piston has moved downwardly sufficiently to relieve the tension of the spring and then the electrodes will slowly separate under the influence of gravity and the retarding effect of the dash-pot, until the movement is arrested by the stops. The strength of the arc deflecting field may be regulated by adjusting the resistance H to shunt more or less current through the magnets D and E.

The invention may be employed in connection with either alternating or direct current circuits and while it has been illustrated in what is considered its best application, it may have other applications and be embodied in different structures. It should not therefore be limited to the application or structure shown.

Having thus described the invention what is claimed is:

1. The combination with electrodes, of a dash-pot connected thereto tending to prevent the separation of the electrodes, a spring securing said dash-pot adapted to be placed under tension upon the movement of said electrodes toward each other.

2. The combination with electrodes, of a dash-pot one member of which is connected thereto, a spring securing the other member of said dash-pot, an electro-magnet and a plunger therefor connected to said electrodes, the member of the dash-pot secured by the spring being adapted to be attracted by said electro-magnet.

3. The combination with electrodes, of a dash-pot the plunger of which is connected with the electrodes, a spring supporting the other member of said dash-pot, an electro-magnet for moving the electrodes to strike the arc, and means whereby the electro-magnet places the said spring under tension.

4. The combination with electrodes tending normally to separate, of an electro-magnet for bringing them together to strike the arc, a dash-pot for retarding the separation of the electrodes, and means for temporarily placing said dash-pot under spring tension

tending to prevent separation of the electrodes when the electro-magnet is deenergized.

5. The combination with electrodes tending normally to separate, of an electro-magnet for bringing them together to strike the arc, a spring supported dash-pot for retarding the separation of the electrodes, and connection between said dash-pot and an armature of said magnet whereby the spring supporting the dash-pot is placed under tension when the arc is struck.

6. The combination of electrodes tending normally to separate, of means for striking the arc, and means for temporarily holding the electrodes firmly in contact under gradually decreasing pressure, substantially as described.

7. The combination of electrodes tending normally to separate, of an electro-magnet for bringing them together and striking the arc, a spring supported dash-pot connected with the electrodes tending to prevent the separation thereof, and means operated by the magnet for placing the spring under tension when the electrodes are drawn together, substantially as described.

8. The combination of electrodes tending normally to separate, of an electro-magnet for bringing them together, and a tension device for temporarily holding the electrodes in contact adapted to be brought into operation by the magnet, substantially as described.

35 9. The combination with electrodes tending to separate, of fixed pivoted supports therefor, means for moving the points of the electrodes toward each other, means for releasing the electrodes from the aforesaid 40 means, a spring supported dash-pot for retarding the separation of the electrodes, and means for placing said spring under tension when the electrodes are drawn together.

10. The combination of electrodes tending normally to separate, of a solenoid magnet provided with two armatures entering the solenoid at opposite ends and adapted to meet therein, a spring supported dash-pot connected to one of the armatures, connec-

tion from the other armature whereby the electrodes are brought together, and connections between the said other armature and the piston of the dash-pot.

11. The combination with electrodes pivotally supported near one end, of means for swinging said electrodes on their pivots to bring the electrode points together and striking the arc, means for holding the electrodes firmly in contact when the arc is struck, and means for releasing the said means.

12. The combination with pivotally supported electrodes, of means for striking the arc, means for holding the electrodes firmly in contact, means for gradually releasing the pressure, allowing the electrodes to separate, and means for limiting the separation of the electrodes.

13. The combination with pivotally supported electrodes, of an electro-magnet and connecting mechanism for swinging the electrodes on the pivots and striking the arc, means for holding the electrodes firmly in contact when the arc is struck, and stops for limiting the separation of the electrodes.

14. The combination with electrodes pivotally supported above their centers of gravity, of means for swinging the electrodes on the pivots and thereby striking the arc, means for holding the electrodes firmly in contact when the arc is struck, and means for allowing the electrodes to gradually separate a fixed distance.

15. The combination with electrodes pivotally supported above their centers of gravity and tending normally to separate, of a vertically movable rod, connected by link arms to the free ends of said electrodes, a spring supported dash-pot connected to the end of said rod and supporting it, and means for elevating said rod to strike the arc and for placing the spring of said dash-pot under tension.

In testimony whereof I affix my signature in presence of two witnesses.
